Primary Examiner — Vy N Koenig*Assistant Examiner* — Kimberly Barnes(74) Attorney, Agent, or Firm — Saidman DesignLaw Group, LLC(57) CLAIM

The ornamental design for a set of tiles, as shown and described.

DESCRIPTION

The sole FIGURE is a front elevational view of a set of tiles showing my new design.

Thickness forms no part of the claimed design. The light grey shading indicates the solid surface of the individual tiles in the tile pattern.

1 Claim, 1 Drawing Sheet(56)
